*Primary Examiner—Ruth McInroy**(74) Attorney, Agent, or Firm—Roy, Kiesel, Keegan & DeNicola***(57) CLAIM**

I claim the ornamental design for a hand held vacuum cleaner, as shown and described.

DESCRIPTION

FIG. 1 is a perspective view of a hand held vacuum cleaner showing my new design;

FIG. 2 is an enlarged front view thereof;

FIG. 3 is an enlarged back view thereof;

FIG. 4 is a left side view thereof;

FIG. 5 is a right side view thereof;

FIG. 6 is a top view thereof; and,

FIG. 7 is a bottom view thereof.
